UNITED STATES PATENT OFFICE.

WILLIAM SCHEER, OF ARVERNE, NEW YORK.

DESIGN FOR A BROOCH.

SPECIFICATION forming part of Design No. 23,459, dated July 17, 1894.

Application filed May 22, 1894. Serial No. 512,122. Term of patent 7 years.

To all whom it may concern:

Be it known that I, WILLIAM SCHEER, a citizen of the United States, residing at Arverne, in the county of Queens and State of New York, have invented and produced a new and original Design for a Brooch or Pendant, of which the following is a specification, reference being had to the accompanying drawings, in which—

10 Figure 1 is an elevation and Fig. 2 a plan view of my design mounted as a brooch.

The leading feature of my design consists in a configuration representing a bird with a series of surface ornaments.

15 In outline the configuration is curved and the surface of the body *a* of the bird is con-

vex, with the spread wings *b*, the one extending above and the other below the body, and with the tail feathers *c* as projecting at one side, and the surface of the body, wings and tail feathers comprises series of grouped and contrasting small circles indicating the series of surface ornaments.

What I claim is—

The design for a brooch or pendant, substantially as shown and described.

Signed by me this 9th day of May, A. D. 1894.

WILLIAM SCHEER.
